[57] **CLAIM**

The ornamental design for a telephone handset housing or similar article, as shown and described.

DESCRIPTION

FIG. 1 is a left side, top and front perspective view of a telephone handset housing or similar article showing our new design;

FIG. 2 is a bottom elevational view thereof;

FIG. 3 is a right side elevational view thereof; and,

FIG. 4 is a bottom plan view thereof.

The broken line showing of an antenna in FIGS. 1-4 and push button in FIG. 1 is for illustrative purposes only and forms no part of the claimed design.

FIG. 1

*FIG. 3**FIG. 2****FIG. 4***
